SHOEMAKING METHOD

Walter P. Field, Brockton, Mass.

Application January 19, 1937, Serial No. 121,258

2 Claims. (Cl. 12—142)

This invention relates to the manufacture of shoes and more particularly to an improved shoe and to a process for making the same.

The main object of my invention is the provision of a cheap shoe having both inside and outside the appearance of a genuine Goodyear welt shoe and having the durability and wearing qualities of a shoe of that character, and the provision of a method for making the same.

Another object of my invention is the provision of a cheap shoe of the welt type, which may have either a leather outer sole or one of rubber composition or similar material.

Another object of the invention is the provision of a method by which a strong, efficient and durable bond between the outer sole and the shoe upper is secured by the vulcanization to the upper of a welt of vulcanizable material, which is permanently attached to the outer sole.

An additional object of the invention is the provision of a simple method for making shoes which eliminates many of the steps heretofore considered necessary in the making of welt shoes and which materially shortens the time consumed in the production of the shoes and materially reduces the cost thereof.

Other objects of the invention will be more particularly set forth and described hereinafter.

My invention contemplates a shoe and method 30 of making the same, in which the outer sole is permanently fastened to the upper by vulcanization thereto of a welt, which is permanently attached to the outer sole. This is accomplished by impregnating the roughened bottom edges of 35 the upper with vulcanizable material, such as rubber latex, containing vulcanizing agents, and by using a welt of vulcanizable material, such as rubber composition. These parts are then coated with a solution made up of one or more vulcanization accelerators dissolved in solvents capable 40 of dissolving the said vulcanizable material, and, after a short interval of time, the coated surfaces are pressed together under a heavy pressure which is maintained for a sufficient time to permit vulcanization to take place.

In this manner, a firm and lasting bond is secured between the welt and the upper, due to the fact that the vulcanization results in an integral bonding body of vulcanized material which permeates and becomes an integral part of both the attached portions, so that they cannot be separated without rupturing one or the other of the attached elements.

Preferably, the welt is provided with an inner 55 beveled portion to which the bottom edges of the upper are vulcanized, and the strength of the bond between these two parts may be increased or diminished by increasing or decreasing the width of the beveled portion of the welt. Preferably, the welt is attached to the outer sole by a

row of edge stitching, which, in addition to fastening the two parts together, has the advantage of simulating the appearance of the welted edge of a Goodyear welt shoe. The welt, however, may be attached to the outer sole in any suitable 5 manner, either by vulcanization by the same method pursued in attaching the welt to the upper, or it may, in some cases, be attached by cement, where the welt and the outer sole are of materials such as rubber composition, which 10 permit the use of cement.

In the embodiment of the invention described hereinafter, rubber is designated as the preferable vulcanizable material used for attaching an outer sole to a shoe upper by vulcanization. 15 This requires, of course, that the vulcanization accelerators used be adapted for dissolving rubber. It is to be understood, however, that my invention is not to be limited to the use of rubber as the vulcanizable material, since there are 20 other vulcanizable substances which may be used in place of rubber, and other solvents especially adapted for those vulcanizable materials. In any event, however, the welt must, in such case, be made of the same vulcanizable material that is 25 used for impregnating the edges of the lasted upper.

In the accompanying drawings illustrating my invention, Figure 1 is a side elevation of a man's shoe constructed in accordance therewith; 30

Fig. 2 is a bottom plan view on an enlarged scale of a lasted upper and inner sole having the surplus material trimmed off, with the edges of the upper ready to be roughened for receiving the bonding material; 35

Fig. 3 is a plan view of the inner face of an outer sole having a welt of vulcanizable material attached thereto, the welt being shown as having an inner beveled portion adapted to be attached to the lasted upper by vulcanization; 40

Fig. 4 is an enlarged cross-sectional view on line 4—4 in Fig. 1;

Fig. 5 is a cross-sectional view similar to Fig. 4 of a modified form of construction having a welt and outer sole made in one piece of rubber composition; 45

Fig. 6 is a cross-sectional view of the welted sole unit shown in Fig. 4;

Fig. 7 is a similar view of the welted sole unit shown in Fig. 5; and 50

Fig. 8 is a side elevation of a portion of the welt.

In the drawings, my invention is shown as exemplified in a man's Oxford shoe of the welt type, but it is to be understood that this is merely 55 for the purpose of illustration and that the invention is also applicable to the manufacture of women's and children's shoes, and, generally, to the manufacture of all kinds of footwear coming under the generic term "shoe." As shown, the 60

shoe comprises an upper designated generally as 10, an inner sole 12, an outer sole 14, and a heel 16. The upper, which may be made in any suitable manner, is shown as comprising outer parts 5 consisting of a pair of quarters 18, a vamp 20, and a tip 22, and inner parts include a lining 24, a box toe 26, and a heel counter 28. The outer sole 14 is provided with a welt 30 fastened thereto.

In the method of making a shoe according to 10 my invention, the shoe upper is first prepared in the usual manner by assembling and fastening the various parts thereof in their proper relations, after which the inner sole 12 is tacked to the last and the prepared shoe upper 10 is fitted over the 15 last ready for the pulling-over operation. The upper is then lasted, and this may be done by any suitable McKay method of lasting, either full cement lasting, step-by-step nail lasting, or staple lasting. A combination of the cement and 20 staple methods is preferred for the lasting operation, and, in carrying this out, the bottom edges and the margin of the outer face of the inner sole are coated with any suitable cement, and the edges of the upper are then pulled over and 25 adhesively fastened to the inner sole, and the sides of the upper are staple-lasting with staples 34 to the inner sole by the well-known Littleway process. In the latter process, the staples are of light construction and are clenched within the 30 inner sole without going through and appearing on its inner surface. Around the toe, the pulled-over edges of the upper may be temporarily held in place to permit the cement to set, by pull-over tacks inserted in the toe portion of the last. The 35 edges of the upper around the heel are preferably lasted by the use of permanent tacks 36, but these edges may be lasted by adhesive alone if desired. After the cement has thoroughly dried or set, the pull-over tacks are withdrawn and 40 the surplus material of the upper, including the box toe and lining around the toe portion of the last, is trimmed off to provide a smooth, flat surface, as shown in Figure 2. The exposed edges of the outer leather parts of the shoe upper are 45 then scoured or roughened in preparation for vulcanizing the outer sole thereto.

My method also includes the preparation of an outer sole unit, comprising an outer sole 14, which 50 may be of leather, rubber composition, or other suitable material, and a welt 30 of vulcanizable material permanently attached to the outer sole. In the preparation of this unit, the outer sole is 55 died out of suitable material to the exact form and dimension required by the last and is prepared in the usual way. The welt is preferably made of molded rubber composition and may be made in various forms, but, preferably, its outer edge portion, which is exposed in the finished shoe, is of uniform thickness with parallel 60 top and bottom faces, and its inner edge portion is beveled on its top face, and the width of the beveled portion 32, although it may be varied to suit varying conditions, must be sufficient to insure a strong and durable bond between that 65 portion of the welt and the edges of the shoe upper when those parts are fastened together by vulcanization. The welt is applied around the margin of the forepart of the sole from the heel breast on one side to the heel breast on the 70 other side, and is permanently fastened to the outer sole by any suitable means, such as stitching 40.

It is important that the welt be sufficiently 75 tough to hold the stitching by which it is fastened to the outer sole and that it be of sufficient hard-

ness, approximately between 90 and 92, in order to retain its form and shape permanently, and that it be susceptible to chemical agents adapted to dissolve rubber and to further vulcanization. Although the welt may be made of various rubber compositions, yet I have found that a composition made according to the following formula gives most excellent results and produces a welt which fully answers the foregoing requirements. This composition is made up of the following ingredients and parts by weight:

	Parts
Crude rubber in smoked sheets	27
Automobile tire reclaim	24
Inner tube reclaim	7 15
Mineral rubber compound	2
"Carbon-X"	9
Vulcanization accelerator ("DPG")	1.7
Carbon black	25.5
"R-Kadox"	2 20
"VGB"	16
Sulphur	1.7

The mineral rubber compound is a natural deposit which is used as a filler and a substitute for rubber and is a commercial product well known under the name "MRX;" the "Carbon-X" imparts toughness to the composition and is a well-known commercial product; "DPG" is a trade name for a well-known vulcanization accelerator used with sulphur for that purpose; "R-Kadox" is a zinc solution used for hardening and is likewise well known under that name; "VGB" is an anti-oxygen agent to retard oxidizing and is well known under said designation; and carbon black is used for imparting toughness and rigidity to the compound, and, at the same time, produces its black appearance.

The welt is formed from the composition by molding and is vulcanized under heat and pressure for from ten to fifteen minutes, so that when it is taken out of the mold, it is not entirely cured but is still subject to further vulcanization.

In attaching the welt to the outer sole, I prefer to use a single line of welt stitching 40, which is 45 located in the outer portion of the welt so as to be visible in the finished shoe. The stitching 40 may be either of the well-known lock or chain forms. When the lock stitching is used, it may be left exposed on the outer face of the outer 50 sole, or it may be laid in a narrow channel cut in the outer face of the sole and covered by a turned-back portion; but in the case of chain stitching, it is preferable to form a channel in the outer face of the sole for concealing it.

The next step in my process consists in impregnating the roughened edges of the upper with rubber capable of vulcanization, and this is preferably accomplished by coating the roughened surfaces with a latex mixture, such, for instance, 60 as a solution of the following composition.

100	parts of cleaned liquid latex	40 to 50%
	rubber content.	
0.4	part colloidal zinc oxide.	
0.4	part colloidal sulphur, and	65
0.75	part of a solution consisting of—	
3	parts of casein (fat free)	
6.2	parts of sodium sulphide	
0.08	part of sodium salicylate	
14.72	parts of distilled water.	70
	The viscosity of this liquid at 20° C. (Engler's method) is 1.5.	

This solution should be liberally applied to the roughened surfaces and brushed in so that it

will penetrate the edges of the upper thoroughly. More than one coating may be applied, but each coating must be allowed to dry thoroughly before the next coating is applied. Normally, a coating 5 will dry in about half an hour. This step of my process may be carried out some days in advance of the next step, since the material in the impregnated edges of the upper is not affected by aging for a period of two months or more.

10 After the edges of the upper have been thoroughly permeated with the latex mixture and have dried, the next step in my process consists in treating those edges and the welt with a solution containing one or more vulcanization accelerators dissolved in solvents capable of dissolving rubber. One solution which is adapted 15 for this purpose comprises the following:

1 part of rubber.
20 99 parts of trichlorethylene.
20 1 part of an accelerator such as a powder made up of —
10 parts of ordinary commercial piperidine
10 parts of dithiocarbamate
25 10 parts of carbon disulphide
50 parts of china clay.

This powder is similar in composition to what is sold on the market under the name "Superac."

30 This solution is applied in any suitable manner to the impregnated edges of the upper and to the beveled portion of the welt, which is previously roughened up to remove the hardened film due to molding and to expose the softer interior. A sufficient amount of the solution should be used 35 to soften up the rubber in the edges of the upper and the welt to an appreciable depth and more than one coat may be applied if necessary. After being coated, the parts are allowed to stand for from five to ten minutes until the rubber components have been partially dissolved and softened, 40 after which the welted sole unit is applied to and spotted on the lasted upper and the parts are subjected to a pressure of at least eighty-five pounds to the square inch for a period of from 45 twelve to twenty minutes.

The pressure is preferably applied by suitable mechanical means and a higher pressure than that specified is of advantage. My experience has been that the higher the pressure and the 50 longer it is sustained within reasonable limits, the stronger is the bond between the welt and the upper.

Under this pressure, the accelerators in the last solution penetrate throughout the rubber in 55 the edge of the upper and the welt and start cold vulcanization which unites in one integral homogeneous body the rubber content present in both parts and securely locks the welt to the upper.

After the shoe is released from the pressure, 60 the heel portion of the outer sole is then nailed around the heel in the usual manner, after which the heel may be applied thereto. The edges of the outer sole and welt may then be trimmed and set, or, if preferred, this operation may be performed before the welted sole unit is fastened to 65 the shoe upper. After this, the shoe is subjected to such further finishing operations as required.

In Figures 5 and 6 of the drawings, the shoe is shown as made with a filler 42, but it may be 70 made without a filler. Any suitable filler may be used, such as a thin, firm, felt filler, which I have found gives the best results, and this filler is preferably applied to the shoe upper directly after it is lasted.

75 My method can be used not only with uppers

having leather outer parts, but also with uppers in which the outer parts are of canvas or other fabrics or other material of a fibrous character capable of being permeated by a solution of vulcanizable material.

Some of the important advantages of my invention are that it eliminates many of the costly operations now involved in producing a genuine Goodyear welt shoe and simplifies the process to an amazing extent; that it eliminates the rough inside of the McKay made shoe, whether produced by lock stitching or other variations of the McKay system; and that it further eliminates the stiff midsole, which is characteristic of the McKay welt and nailed shoes, and, consequently, results 10 in producing a more flexible and resilient shoe than any produced by either of the systems mentioned above. In short, my invention permits the production of a shoe having the appearance, both inside and out, the durability and wearing 15 qualities, and other advantages of high-grade Goodyear welt shoes at a production cost of cheap shoes.

One of the advantages in using a welt of rubber composition, or similar moldable material, is 20 that the exposed face of the welt may be provided with transverse corrugations 44 more closely simulating the appearance of a Goodyear welt, as shown in Figure 3, which corrugations may be 25 formed in the molding process, and, therefore, are permanent and are not affected by wear. The same indentations in a leather welt disappear 30 with the absorption of moisture by the leather, so that the welt in time becomes comparatively 35 smooth.

Another important advantage which flows 40 from the use of my invention in shoes having rubber composition soles is that the soles may be made of a color to harmonize with the color of the shoe upper. During the past few years, there has been a growing tendency in the shoe manufacturing industry to produce shoes having uppers of all shades of color. This tendency, which has heretofore been largely confined to 45 women's shoes, is now spreading to men's shoes, and it not only includes uppers of different colors, but also combinations of different colors in the same shoe. Attempts have heretofore been made to carry out these color schemes in shoes having leather soles by painting the soles and the welts, 50 if provided with welts, or by coating them with a veneer. This has not proved satisfactory, however, because the paint or veneer soon wears off and disappears. Rubber composition, however, can be made in any color, and soles and 55 welt of this material can be made to match exactly the color of the shoe upper, or can be made of a different color in harmony with the color of the shoe upper, and the color of the sole and welt is permanent. The coloring of rubber composition is done in the mixing and molding of that material, so that there is no appreciable increase in its cost, whereas, the coloring of a leather sole and a leather welt involves additional operations which increase the cost of the 60 shoe.

Another important advantage of a shoe constructed by my method is that it is substantially waterproof, because the joint between the edges of the upper and the welt is closed by a body of 70 vulcanized rubber, which is integral with the edges of the upper and the welt, and, thereby, effectually prevents the entrance of moisture.

Although I have described herein, as a part of my invention, the attachment of the welt to 75

the outer sole by stitching or vulcanization, yet it may be accomplished by other means, such, for instance, as stapling the welt to the outer sole by staples set in a channel formed in the outer surface of the sole and clenched invisibly in the welt. This form of construction may be found of advantage in very cheap shoes made in accordance with my invention. Also the welt may be formed integrally with the outsole, as shown in Figs. 5 and 7 of the drawings, and where in the claims the welt and outsole are defined as attached one to the other, this language is intended to cover such integral construction of a sole unit having a welt portion and an outsole portion.

It is to be understood that my invention is not to be limited to the precise forms herein shown and described, since it may be embodied in various other forms, all within the scope of the following claims.

What I claim is:

1. A method of making shoes consisting in lasting an upper over the marginal edges of an inner sole, roughening the lasted edges of said upper and then impregnating them with a vulcanizable material containing a vulcanizing agent, attaching a partially vulcanized welt of vulcanizable material along the margin of an outer sole, said welt having an inner longitudinal bevelled portion of substantial width equaling

the width of the lasted edges of said upper, coating said impregnated lasted edges of said upper and the bevelled portion of said welt with a solution containing a vulcanization accelerator dissolved in a solvent capable of dissolving said vulcanizable material of said welt and said edges, and then placing said outer sole against said lasted upper and subjecting said parts while in tacky condition to a heavy pressure continued for a sufficient time to vulcanize said welt to said lasted edges for fastening said outer sole to said upper.

2. The method of attaching to a lasted upper a welt having an inner longitudinal bevelled portion of vulcanizable material which method consists in roughening the lasted edges of the upper and then impregnating them with a vulcanizable material containing a vulcanizing agent, coating said impregnated edges and the bevelled portion of the welt with a solution containing a vulcanizing accelerator dissolved in a solvent capable of dissolving the vulcanizable material of the welt and edges, positioning the bevelled portion of the welt against the lasted edges of the upper, and subjecting the parts while in a tacky condition to a heavy pressure continued for a sufficient time to vulcanize the welt to the lasted edges of the upper.

WALTER P. FIELD. 30
